SANITARY NAPKIN

Alfred M. Beyer, Jr., Flushing, N. Y.

Application June 15, 1935, Serial No. 26,745

3 Claims. (Cl. 128—290)

This invention relates to new and useful improvements in a sanitary napkin.

The invention has for an object the construction of a sanitary napkin which may be used without chafing the skin or causing irritations.

This invention has for an object the provision of cotton or similar soft absorbent filler members along the edges of the napkin arranged in such a manner as to prevent, or materially reduce, irritation when the napkin is worn.

Still further the invention proposes a novel arrangement for connecting the cotton filler members with the absorbent pad of the napkin.

Another object of the invention is to construct the napkin with a reduced central portion in which the cotton filler members may be readily set.

Still further the invention contemplates an arrangement whereby the cotton filler members may be adjusted to various positions for the convenience of a wearer.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a sanitary napkin with the casing thereof removed to disclose interior parts.

Fig. 2 is a sectional view taken on the line 2—2 of Fig. 1.

Fig. 3 is a plan view of a napkin constructed according to another embodiment of this invention, a portion of the casing shown broken away.

Fig. 4 is a sectional view taken on the line 4—4 of Fig. 3.

Fig. 5 is a perspective view of the absorbent pad portion of the napkin shown in Fig. 3.

Fig. 6 is a plan view of the absorbent pad portion and the cotton filler members of a napkin constructed according to another embodiment of the invention.

Fig. 7 is a horizontal sectional view of a napkin constructed according to another modification of the invention.

The invention relates particularly to the absorbent pad within the gauze casing of a sanitary napkin. More particularly, it is proposed to con-

struct the absorbent pad 10 in conventional fashion of several layers, but to distinguish it from prior constructions in arranging the central portion 10^a thereof relatively reduced in plan view in comparison with the end sections 10^b thereof, so as to permit the center portion of the napkin to follow the contours of the body and still retain a substantially horizontal transverse position. Cotton or similar soft filler members 11 are mounted on the sides of the reduced portion 10^a of the absorbent pad. These cotton filler members are of the same height as the pad 10 and are adapted to lie within the compass of the enlarged ends thereof. The filler members 11 are restrained from free longitudinal motion by reason of having their inner sides 11^a of serrated contour fitting into corresponding serrations upon the sides of the portion 10^a of the absorbent pad and are adapted to bend readily so as to follow the contour of the body smoothly without buckling, thus making a close fitting between the pad and the body.

This pad with the cotton filler members is then engaged in the conventional gauze casing (not shown in this form of the invention).

In Figs. 3—5 inclusive another embodiment of the invention has been illustrated which consists of an absorbent pad 10 having a central reduced portion 10^a and enlarged ends 10^b. Cotton or like filler members 11' are arranged upon the sides of the reduced portion, but are of a materially smaller length than the length of the reduced portion. These cotton filler members have their inner faces formed with serrations 11^a adapted to engage corresponding serrations on the sides of the reduced portion 10^a. As the center members 11' are of shorter lengths than the reduced portion 10^a, they may be set at various longitudinal positions for the convenience of a wearer of the device to avoid chafing at one area or another area of the skin. A conventional gauze casing 12 is engaged over the absorbent pad and the cotton filler members to hold them in an intact unit.

In Fig. 6 another embodiment of the invention has been disclosed which is very similar to the form shown in Figs. 3—5 inclusive, distinguishing merely in the construction of the serrations 11^{aa} upon the contacting faces of the filler members and the reduced area 10^a of the absorbent pad. More particularly, these serrations are of a continuous curve, contrasted with the prior construction in which sharp points were used.

In Fig. 7 another modified form of the inven-

tion is disclosed in which there is an absorbent pad 10' having a reduced central area 10^{aa} adapted to accommodate small cotton or like filler members 11''. The contacting faces of the cotton filler members and the reduced portion 10^{aa} of the pad are smooth so that the members may assume various adjusted positions along the sides of the pad.

5 Adhesive tape 14 or similar holding means are mounted between the members 11'' and the pad 10' to hold the members in fixed positions. Any other suitable holding means may also be used to hold the side members to the pad. The conventional gauze casing 12 encases the absorbent 10 pad and the members 11''.

15 It is to be understood that the shape of the napkin and of the filler members may be changed as desired, also that cotton or similar material may be wrapped about the entire center portion of the napkin.

20 While I have illustrated and described the preferred embodiment of my invention, it is to be understood that I do not limit myself to the precise construction herein disclosed and the right 25 is reserved to all changes and modifications coming within the scope of the invention as defined in the appended claims.

Having thus described my invention, what I

claim as new, and desire to secure by United States Letters Patent is:

1. In a sanitary napkin, an absorbent pad having a reduced central area, cotton or like filler members located in intimate contact with the sides of said reduced area, the reduced central area having concaved sides, and means for holding said filler members in various positions along said sides.

2. In a sanitary napkin, an absorbent pad having a reduced central area, cotton or like filler members located in intimate contact with the sides of said reduced area, the reduced central area having concaved sides, and the contacting faces of the cotton filler members and the said sides being formed with inter-engaged portions by which the filler members are held in various fixed positions.

3. A sanitary napkin, comprising an absorbent pad having concaved sides, cotton or like filler members located in intimate contact with said concaved sides, and means for holding said filler members in various adjusted positions on the sides in said pad, comprising inter-engaging serrations in the contacting faces of the filler members and the concaved sides.
